WITNESS:

UNITED STATES PATENT OFFICE.

CLARENCE E. FLINCHBAUGH, OF LIMA, OHIO.

STAKEHOLDER.

Application filed July 2, 1924. Serial No. 723,813.

To all whom it may concern:

Be it known that I, CLARENCE E. FLINCHBAUGH, a citizen of the United States, residing at Lima, in the county of Allen and State of Ohio, have invented new and useful Improvements in Stakeholders, of which the following is a specification.

My present invention pertains to vehicle bodies such as are equipped for the holding of stakes.

One object of the invention is the provision of an efficient lock calculated to prevent casual movement, rattling and loss of a stake.

Another object is the provision of a stake holder that is not liable to be affected by the swelling of wood in wet weather.

Another object is the provision of a stake holder of such character that friction or frictional contact will not render difficult the removal of a stake.

Another object is the provision of a stake holder of such character that the stakes may be channel iron, angle iron or wood.

Another object is the provision of a stake holder construction whereby a platform can be made standard to receive individual stakes, stake sections, and embrace panels and tops.

Another object is the provision of improved means for locking a stake in a holder.

Other objects and practical advantages of the invention will be fully understood from the following description and claims when the same are read in connection with the drawings, accompanying and forming part of this specification, in which:

Figure 1 is a vertical section of the preferred embodiment of my invention taken in the plane indicated by the line 1—1 of Figure 4.

Figure 2 is a broken exterior elevation illustrative of the improvement.

Figure 3 is an enlarged detail vertical section taken in a plane parallel to that of Figure 1.

Figure 4 is a top plan view of the preferred embodiment.

Figure 5 is an end elevation of said embodiment.

Figure 6 is a detail perspective of the angle metallic member which constitutes an important part of my invention.

Figures 7, 8 and 9 are views of a modification hereinafter explicitly referred to.

Similar numerals designate corresponding parts in Figures 1 to 6 to which reference will first be made.

In accordance with my invention cross beams 1 are arranged under the floor 2 of a vehicle body, and an angle iron 3 and a metallic strap 4 are extended throughout the length of the body, the strap 4 being spaced outwardly from the vertical portion of the iron 3 and being arranged in parallelism with said vertical portion for the interposition of wooden sections 5, the said wooden sections 5 being connected to the angle-iron 3 and the strap 4 by bolts 6, and the angle-iron 3 and the beams 1 and floor 2 being connected together by bolts 7 on which are nuts 8.

Arranged alongside the beam 1 illustrated and under the floor 2 is a wooden section 9, said section 9 being connected to the angle-iron 3 by bolt 10 and nut 11 and being also connected to the floor 2 by a wood-screw 12. It will also be noted by particular reference to Figure 1 that the bolt 10 and the screw 12 serve for the additional connection of the metallic angle member 13, the horizontal portion of said member being disposed under the wooden section 9. The outer end of the horizontal arm of the member 13 is bifurcated as designated by 14, and the upright arm of the said angle member is provided with side walls 15 disposed at opposite sides of the said bifurcation and is also provided with an upright loop 16, the sides of the said loop 16 being integral with the side walls 15 as illustrated. A space 17 is afforded between confronting ends of the wood sections 5, and in the said space rests the said upright loop 16.

Pivoted at 18 in the loop 16 of the angle member is a swinging bar 19 having at its outer side a teat 20 on which is arranged one end of a coil spring 21. The opposite and outer end of the said coil spring 21 receives a projection 22 on a shaft 23 carried by and extending between the side portions 100 of the upright loop 16.

Pivotedly mounted on the shaft 23 is a lever 24 with a hook 25 and connected by a link 26 with the bar 19. When the lever

24 is in the position shown in Figure 3 the bar 19 will manifestly be retained in the position shown in Figure 3. When, however, the lever 24 is swung downwardly into 5 the position shown in Figure 1, the spring 21 will operate to yieldingly maintain the bar 19 in the position shown in Figure 1 so as to enable the said bar 19 to operate after the manner of a latch to hold against 10 upward movement of stake 30, the said stake 30 extending down in the space 17 and bearing at its lower end on the horizontal arm of the angle member 13 as clearly shown in Figures 1 and 3. I prefer to employ a 15 stake 30 of channel form as illustrated, though I do not desire to be understood as confining myself to a channel form stake; and I also prefer to provide the metallic stake 30 with a wooden portion 31 connected 20 by bolts 32 to the stake, but it is manifest that the said wooden portion and its connections may be altogether omitted without affecting my invention. It will be readily noted that the stake 30 receives between 25 its side walls 33 the upstanding portion of the angle member 13, and it will also be observed that the stake 30 is provided at 40 with an opening to receive the lower end of the latch bar 19, the portion of the stake 30 below the opening 40 being preferable, though not necessarily, reinforced as 45 designated by 41 to prolong the usefulness of the portion of the stake that is engaged by the latch bar 19 after the manner shown in Figure 1.

Carried at the inner side of the stake 30 and connected to the stake by bolts 50 or other appropriate means is a hook-like metallic member 51 that is adapted when the stake 30 is moved downwardly into the space 17 to engage the upper edge of the angle-iron 3 so as to co-operate with the said angle-iron in preventing outward deflection of the stake.

45 In the practical use of my improvement it is simply necessary to socket the lower end of the stake 30 in the space 17 and so that the lower end of the stake bears on the horizontal arm of the angle member 13, 50 and so that the member 51 hooks over the angle-iron 3 and to then move the lever 24 from the position shown in Figure 3 to that shown in Figure 1, whereby the latch bar 19 will be caused to engage the stake 30 and 55 strongly and securely lock the stake so that it is held against casual upward movement and is also held against rocking. In this connection it will be appreciated that the placing of the stake does not involve frictional wear of any part of the construction; and it will also be appreciated that the parts are not liable to be affected by the swelling of wood in wet weather. When it is desired 60 to remove the stake it is simply necessary to move the lever 24 from the position shown

in Figure 1 to the position shown in Figure 3, whereupon the stake 30 may be lifted out of the space 17 without interference from any part of my improvement and without the necessity of the operator having to overcome any frictional contact. 70

By particular reference to Figures 7, 8 and 9 it will be understood that the angle member 13^x is provided with an upright arm 15^x, and that pivoted to the said upright arm 15^x is a swinging bar 19^x having a bifurcated end portion 20^x which straddles the upper portion of the arm 15^x. Interposed between the arm 15^x and the swinging bar 19^x is a spring 21^x, attached to the arm 15^x, and pivotally connected to the swinging bar 19^x is a bail 26^x which straddles the upright arm 15^x below shoulders 30^x thereon as illustrated. Pivoted on the right of the bail 26^x and disposed back of the upright arm 15^x is a lever 24^x of cam type, the said lever 24^x being arranged as illustrated when it is desired to maintain the swinging bar 19^x in the position illustrated to hold the stake against upward movement and 90 being designed to be swung to a position at right angles to the position shown when it is desired to retract the swinging bar 19^x against the action of the spring 21^x for the disengagement of the swinging bar from the 95 stake to permit of removal of the latter. Manifestly the construction shown in Figures 7, 8 and 9 is a simplification of that shown in Figures 1 to 6, and at the same time is strong and durable and adapted to be 100 operated with facility, and therefore I prefer to employ the construction shown in Figure 7, 8 and 9 over that shown in Figures 1 to 6.

Having described my invention, what I claim and desire to secure by Letters-Pat- 105 ent, is:

1. The combination of the floor of a vehicle body, an angle-iron superimposed on and fixed to said floor, stake-supporting means disposed below and fixed with respect 110 to the floor, a stake bearing at its lower end on said means and having a hook-like member to engage over the upright portion of said angle-iron and means carried by said stake-supporting means for engaging and preventing upward movement of the stake; the said stake-supporting means being in the form of an angle member having an upright portion, and the said means for holding the stake against upward movement comprising a 115 spring-pressed latch bar carried by the upright portion of the angle member and a lever whereby said latch bar can be detachably secured in retracted and idle position.

2. The combination of a floor of a vehicle body, an angle iron fixed thereon, an angle member fixed with respect to the floor and having an upright portion, a stake having a portion hooked over the upright portion 120 of the angle-iron, and means carried by the 125

upright portion of said angle member for engaging the stake and preventing upward movement thereof said means extending inwardly and downwardly from said upright portion.

3. The combination of the floor of a vehicle body, an angle-iron fixed thereon, a stake having a hook-like portion engaged over the upright portion of the angle-iron and also having an abutment, an angle member disposed below and fixed to the floor and having an upright portion, a latch bar pivoted to said upright portion of the angle member and adapted to engage said abutment of the stake, a spring backing the latch bar, and a lever arranged to cooperate with the upright portion of the angle member and connected with the latch bar for holding said bar detachably in idle position.

4. The combination of the floor of a vehicle body, an angle-iron fixed thereon, a metallic strap spaced outwardly from the upright portion of the angle-iron, sections interposed and secured between the angle-iron and said strap and having a space between confronting ends thereof, a stake removably arranged in said space and having a hook-like portion engaged with the angle-iron and also having an abutment, an angle member having a horizontal portion fixed to the floor and also having an upright portion, and means carried by said upright portion of the angle member for engaging the stake and preventing upward movement of said stake.

5. The combination of the floor of a vehicle body, an angle-iron fixed thereon, a metallic strap spaced outwardly from the upright portion of the angle-iron, sections interposed and secured between the angle-iron and said strap and having a space between confronting ends thereof, a stake removably arranged in said spaces and having a hook-like portion engaged with the angle-iron and also having an abutment, an angle member having a horizontal portion fixed to the floor and also having an upright por-

tion, and means carried by said upright portion of the angle member for engaging the stake and preventing upward movement of said stake; the said upright portion of the angle member being of loop form and the said means including a latch bar pivoted in said upright portion, a spring backing said latch bar, and a lever fulcrumed in said upright portion, and a connection between the lever and the latch bar for detachably securing the latter in idle position.

6. The combination of the floor of a vehicle body and stake, an angle member fixed with respect to the floor and having an upright portion, a latch bar pivotally connected to said upright portion for preventing upward movement of the stake relative to the floor and the angle member, a spring in interposed relation between the upright portion of the angle member and the latch bar, a cam lever disposed back of the upright portion of the angle member, and a connection between said cam lever and the latch bar.

7. The combination of the floor of a vehicle body and stake, an angle member fixed with respect to the floor and having an upright portion, a latch bar pivotally connected to said upright portion for preventing upward movement of the stake relative to the floor and the angle member, a spring strip secured in interposed relation between the upright portion of the angle member and the latch bar, a cam lever disposed back of the upright portion of the angle member, and a connection between said cam lever and the latch bar; the said upright portion of the angle member being provided with intermediate abutments or shoulders, and the connection between the latch bar and the cam lever being in the form of a bail disposed below said shoulders or abutments and pivotally connected to the cam lever on its bight.

In testimony whereof I affix my signature.

CLARENCE E. FLINCHBAUGH.
